UNITED STATES PATENT OFFICE.

THOMAS E. COLEMAN, OF MADISON, WISCONSIN, ASSIGNOR TO MADISON-KIPP CORPORATION, OF MADISON, WISCONSIN, A CORPORATION OF WISCONSIN.

LUBRICATOR.

Application filed September 2, 1920. Serial No. 407,641.

To all whom it may concern:

Be it known that I, THOMAS E. COLEMAN, a citizen of the United States, residing at Madison, in the county of Dane and State of Wisconsin, have invented certain new and useful Improvements in Lubricators, of which the following is a specification.

This invention pertains to force feed lubricators and has to do more particularly with that class of lubricators wherein a plurality of pumps or units is employed to force the oil to the separate or various points to be lubricated.

The invention has for one of its objects a construction which enables one to readily withdraw at one and the same time from the combined casing and reservoir all of the operative units, when for one or another reason such withdrawal becomes necessary or desirable, and this without the displacement of the power and the manually actuated shafts through the operation of either of which the mechanism is operated.

A further object of the invention is to provide a special form of ratchet drive for the actuating mechanism, the construction being such that the possibility of non-operation is reduced to a minimum.

A still further object is to provide a special form of eccentric mechanism for actuating the pump elements.

With these and other objects in view reference will be had to the annexed drawings, wherein,—

35 Fig. 1 is a sectional elevation of the structure wherein two pumping or forcing units are disclosed;

Fig. 2 is a vertical longitudinal sectional view;

40 Fig. 3 is a transverse vertical sectional view;

Fig. 4 is a detail sectional elevation illustrative of the ratchet mechanism;

Fig. 5 is a similar view of one of the 45 pump elements and the allied volume controlling means;

Figs. 6 and 7 horizontal sectional views taken through the pump units and showing the parts in different positions;

Fig. 8 is a perspective view of the adjustable sleeve employed to control the volume of oil which may be ejected by the piston;

Fig. 9 is a similar view of one of the pistons;

Fig. 10 a perspective view of a modified form of one of the pistons;

Fig. 11 a transverse sectional view thereof on the line XI—XI of Fig. 10.

Figs. 12 and 13 sectional elevations showing such a piston in its different operative positions;

Fig. 14 a side elevation of a modified form of eccentric;

Fig. 15 a transverse sectional view on the line XV—XV of Fig. 14; and

Fig. 16 a perspective view of the two strap elements.

The employment of a plurality of pump units is contemplated, the units being alike in form and in operation and while only two are shown it will be readily appreciated that one or more may be employed and that any number may be connected up and actuated by the operating mechanism common to all.

In the drawings, and referring first to Figs. 1 to 9 inclusive, 1 denotes the combined reservoir and casing preferably provided with attaching lugs 2 whereby the structure may be secured in position. The cover, which is made sufficiently heavy to be rigid and firm, is denoted by 3 and forms the support for the pump elements, the bodies of which are denoted generally by 4. Inasmuch as the pumps are alike in form the various parts will be similarly lettered. Said bodies are directly secured to the inner face of the cover by plug screws 5 which hold the bodies firmly in place and close the openings in the cover through which the screws extend. A cylinder 6 is formed in the body, said cylinder being provided with a port 7 (Fig. 3) which opens into a conduit 8 formed in the body casting. A fitting 9 is screwed into the upper enlarged end of the passage and a pipe 10 extends therefrom to the part to be lubricated. A jam or lock nut 11 holds the fitting in position.

65

75

85

90

95

tion and the fitting also assists in securing the casting or body 4 to the cover 3.

A lateral extension 12 is formed on the body 4, said extension being bored to provide a passage 13 opening into the cylinder and producing a cylinder port 14 opposite port 7. An intake pipe 15 provided with a strainer 16 at its lower end is screwed into an opening 17 which communicates with 10 the passage 13.

Mounted within the cylinder for endwise adjustment is a sleeve 18 (Fig. 8) which varies or controls the volume of oil which may be ejected by the pump piston 19 at 15 each stroke. Said sleeve is provided with oppositely disposed elongated ports 20 and 21, and a third elongated spill-way port 22 which is in register with a port 23 formed through the side of the cylinder.

20 Secured to the lower end of the sleeve is an arm 24 having two threaded openings 25 and 26 formed therein. A stem 27 is threaded into opening 25, said stem passing freely through a bracket 28 extending from 25 body 4 and being held against endwise movement by collars 29 and 30 secured to the stem. At its upper end the stem is in operative engagement with a rotatable head or button 31 swiveled in the cover 3. A nut 30 32 is secured to the lower end of the stem and underlies the arm 24. Threaded into opening 26 is a limiting stop taking the form of a bolt 33, (Fig. 5), the bolt passing freely through bracket 28 and susceptible of being 35 turned in or out the arm 24 by the insertion of a suitable tool through an opening formed in the cover, which opening is normally closed by a plug 34; or said stop may be set prior to the placement of the parts with- 40 in the casing when it is desired, for instance, to prevent the parts from being so regulated that the pump cannot eject an amount of oil below a predetermined minimum. By raising and lowering the sleeve through 45 manipulation of head 31 the amount of oil ejected at each impulse of the pump may be regulated and determined, as will presently appear.

Piston 19 is provided with a vertically disposed port or channel way 35, said way extending to the upper end of the piston or plunger, and at its lower end communicating with a circumferentially disposed way or channel 36, which in turn communicates 55 with a short way or channel 37. Port or channel way 35 forms the intake for the pump and likewise with way 36 and way 37 forms the spill discharge channel for the cylinder. Piston 19 is also provided with 60 a vertically disposed port or channel way 38 at its upper end through which the oil is forced from the cylinder on its way to the part to be lubricated.

The pistons or plungers are each operat-

ed by a wabbling eccentric composed of two parts, 39 and 39^a, which eccentric imparts an up and down movement to the piston and also an oscillatory movement, such double motion being transmitted through strap 40, yoke 41 and rocker block 42, 70 which latter is pivotally mounted in the lower slotted ends of the piston.

With the parts in the position shown in Fig. 3 the piston or plunger is about to begin its downward intake stroke. At such 75 time channel or way 35 is in communication with the intake pipe 15 through port 14 and port 20 in the sleeve 18. As the plunger moves downwardly it is given a partial rotation by the eccentric, the movement being most abrupt as the plunger reaches the bottom of its stroke so that groove 35 is carried out of line with the intake ports 14 and 20 and channel way 38 is brought into alignment with port 21 of the measuring 85 sleeve 18 and port 7 (see Fig. 7 and the right hand pump unit Fig. 2). As the plunger is forced upwardly the oil passes from above the same down through way 38, through port 21 in sleeve 18 and port 7 90 to the point of discharge. When the piston is elevated to such an extent that way 38 passes out of registry with the discharge ports, channel or way 37 passes into registry with the spill port 22 of sleeve 18 and 95 the oil above the piston passes down channel 35 into cross channel 36 and through channel 37, port 22 and port 23 back to the reservoir.

By moving or adjusting the measuring or 100 control sleeve 18 upwardly a greater amount of oil is forced out of the discharge ports 21 and 7 than when the sleeve is lower, due to the fact that the channel way 38 registers with these ports for a greater 105 part of the upward or forcing stroke of the piston. Moreover the spill way channel 37 cannot register with the spill ports 22 and 23 until the lower end of way 38 has passed above port 21, and this occurs late in the 110 upward or impulse stroke of the piston owing to the fact that the ports in the sleeve occupy a relatively higher position. The elongated form of the ports 20, 21 and 22 in the sleeve 18 takes care of this action. 115

As will be seen upon reference to Fig. 2 the eccentric elements are mounted on a shaft 43 and are provided with interlocking lugs 44 which serve to lock the eccentrics together and to suitable actuating devices. 120 At the right of Fig. 2 the element 39^a engages a shouldered sleeve 45 which is journaled in a hanger 46 secured to and extending downwardly from the cover 3. Said sleeve is in driving engagement with a cross 125 rib 47 formed on a head 48 carried at the inner end of a stub shaft 49 mounted in a fixed bearing 50. A disconnectible actuati-

ing crank 51 is mounted on the outer end of the shaft and through which the shaft may be manually actuated when desired.

The opposite end of the shaft extends into a somewhat longer sleeve 52 journaled in a second hanger 53 which sleeve is in engagement with a cross rib 54 formed upon a head 55 of a second stub shaft 56 which is mounted in a bearing 57. A lever 58 is secured to the outer end of the shaft and is adapted to have a swinging or oscillating movement imparted thereto through a pitman 59 (or other suitable device) deriving its power from any suitable source. 10

15 Mounted on shaft 43 between hanger 53 and the adjacent eccentric is a ratchet wheel 60, the hub whereof is in interlocking engagement with the adjacent eccentric element 39. The teeth of the wheel are 20 preferably of V-form as illustrated with the adjacent faces of the adjacent teeth standing at substantially right angles to each other so that the impelling dog or ratchet 61 (see Fig. 4) will take a full and even bearing against the tooth with which it may contact. Said dog is formed integrally with and extends from a pair of laterally extending wings 62 swiveled upon a supporting pin 63 mounted in the outer end of 25 a rocker arm 64. The dog is held in engagement with the wheel through the agency of a spring 65 encircling the pin, one end bearing against the dog and the other against a lug 66 struck up from the rocker 30 arm. A similarly formed stop dog or pawl 67 is mounted on a pin 68 secured to hanger 53, the stop lug 69 for the spring 70 being struck up from the hanger. The rocker arm 64, (see Fig. 2) is provided with a hub 35 40 71 which encircles sleeve 52 and is attached thereto in any suitable manner as by screws 72 or by means of a pressed fit. Inasmuch as the sleeve 52 is driven or oscillated by shaft 56 the rocker arm will be moved back and forth thereby and as a consequence a 45 step by step movement will be imparted to the ratchet wheel and consequently to the eccentrics thereby actuating the piston or pumps. It has been demonstrated in actual 50 practice that with a pawl and ratchet mechanism of the type above set forth that there is no slippage and the drive is therefore positive and accurate. A bracket 73 (see Fig. 2) is secured to hanger 53 and a 55 strainer 74 is held thereby, the same having a reduced upper end 75 producing a shoulder which takes against the under face of cover 3. A suitable cap 76 is provided for the upwardly extending end 75.

60 It is thought that the operation of the lubricator will be understood from the foregoing description. Suffice it to add that the same may be regulated so that each pump element will discharge the desired quantity 65 of oil and that such action is positive. When

for any reason it is desired to remove and inspect the operative parts it is only necessary to remove the cover fastenings and bring the cross ribs 47 and 54 to vertical position whereupon the cover may be raised 70 withdrawing therewith the entire mechanism leaving the driving shafts or elements 49 and 56 in place.

In Figs. 10 to 13 inclusive, a modified form of plunger or piston is illustrated. Under 75 this construction the vertically disposed discharge port or channel 38 is present, as is also the intake port or channel 35. The latter, however, instead of communicating at its lower end with a circumferential way, as 80 36, is in communication with a passage or channel 77 which passes through the plunger body terminating in a port or opening 78 which is the equivalent in its action and function with the spill port or channel 37. 85 Instead of forming the eccentric body in two parts, as 39 and 39^a, as heretofore described, the construction shown in Figs. 14 to 16 inclusive may be employed. Under this construction the eccentric is formed of a single piece or casting 79, the end being provided respectively with the notches 80 and lugs 81, as under the former construction. The body is provided with an enlargement 82 in which is formed an eccentric and laterally inclined groove or seat for the reception of the strap. The strap is in this instance formed of two pieces (see Fig. 16) a yoke 83 having trunnions 84 and a filler block 85, the yoke being provided with 100 downwardly extending fingers 86, preferably offset, which take into offset seats 87 formed in the block 85. The elements 83 and 85 may be secured together in any suitable manner, as by rivets passed through openings 105 formed in the overlapping portions of the members, or they may be secured by electric spot welding. The strap thus formed is connected to the piston or plunger of the pump through the medium of the two-part yoke 41 110 115 which is journaled upon the ends of the pivoted blocks 42 mounted in the lower end of the piston.

It will be understood, of course, that in the broader aspect of the invention I do not 115 desire to be limited to the specific means shown for actuating the lubricator, as any suitable form of driving mechanism may be employed and varied according to the service conditions which obtain.

120 What is claimed is:

1. In a lubricator, the combination of a reservoir for the lubricant; a removable cover therefor; lubricant forcing mechanism suspended from said cover; actuating means for said mechanism extending into the reservoir; and a sliding coupler between said means and mechanism and serving to connect the same.

2. In a force feed lubricator, the combina- 130

tion of a reservoir for the lubricant; a removable cover therefor; a force pump attached to and suspended from said cover; an eccentric for operating said pump; an actuating shaft extending into the reservoir through a fixed bearing; and a freely separable connection intermediate said shaft and the eccentric, whereby the cover and the parts carried thereby may be readily removed and as readily replaced.

3. In a force feed lubricator, the combination of a reservoir for the lubricant; a removable cover therefor; a pair of oppositely disposed actuating stub shafts extending into the reservoir; an intermediate shaft; means attached to the cover for supporting the intermediate shaft; a pump suspended from the cover; an eccentric for the pump mounted on the intermediate shaft; and separable connections between the eccentric and the actuating stub shafts.

4. In a force feed lubricator, the combination of a reservoir adapted to hold the lubricant; a cover therefor, pumps secured to the under face of the cover, the discharge ports whereof are in communication with the parts to be lubricated; eccentrics for operating said pumps; hangers extending downwardly from the cover; a shaft upon which the eccentrics are mounted; sleeves carried by the hangers and forming bearings for the shaft; a stud shaft mounted in a fixed bearing in the side wall of the reservoir; and readily detachable connections between said stub shaft and the adjacent sleeve whereby upon removal of the cover the various elements of the structure will be drawn from the reservoir.

5. In a force feed lubricator, the combination of a reservoir; a cover; a plurality of pumps supported from the under side of the cover; a pair of oppositely disposed stub shafts extending inwardly through the side walls of the reservoir; hangers extending downwardly from the cover; a sleeve mounted in each of said hangers, said sleeves having a readily disengageable connection with the stub shafts aforesaid; a shaft mounted in the sleeves; a ratchet wheel mounted upon the shaft adjacent one of said sleeves; a rocker arm secured to said sleeve; a pawl carried by the rocker arm and adapted to engage the ratchet wheel; an eccentric for each pump mounted on the last named shaft; and driving connections between said eccentrics and between the eccentrics and the ratchet wheel and the sleeve next adjacent said eccentrics.

6. In a force feed lubricator, the combination of a reservoir adapted to contain the lubricant to be forced to the bearings to be lubricated; a pair of hangers secured to the under face of the cover projecting downwardly into the reservoir when the cover is in place; a stub shaft extending inwardly

through a fixed bearing located at one side of the reservoir; a sleeve mounted in the hanger adjacent said stub shaft and having a sliding interengagement therewith; a crank mounted on the stub shaft for manual actuation thereof; a second stub shaft mounted in a fixed bearing located in the opposite wall of the reservoir from that of the first named shaft; a second sleeve mounted in the other hanger, said sleeve having a sliding interengagement with said stub shaft; a third shaft supported by said sleeves and extending across the space between the same; a ratchet wheel mounted loosely upon said last named shaft; a rocker arm secured to that sleeve adjacent the ratchet wheel; a pawl carried by the arm and cooperating with the ratchet wheel; an eccentric for each pump mounted upon the third named shaft; and connections between the eccentrics, the ratchet wheel and the first mentioned sleeve.

7. In a force feed lubricator, the combination of a cylinder having intake, exhaust and spill ports formed therein; a sleeve mounted within said cylinder and adjustable lengthwise thereof to control the capacity of the lubricator, said sleeve having ports which correspond to the ports aforesaid; a piston mounted in the sleeve, said piston being provided with a groove or channel in its side wall adjacent its upper end, a second groove or way formed in its opposite wall and extending downwardly to a point below the termination of the first mentioned groove, said last named groove opening into a way or channel extending through the piston; and means for actuating the piston to impart endwise and oscillatory movements thereto to bring the various ports and passages into cooperative relation.

8. In a force feed lubricator, the combination of a cylinder having intake, exhaust and spill ports formed therein; a sleeve mounted within said cylinder and adjustable lengthwise thereof to control the capacity of the lubricator, said sleeve having ports which correspond to the ports aforesaid; a piston mounted in the sleeve, said piston being provided with a groove or channel in its side wall adjacent its upper end, a second groove or way formed in its opposite wall and extending downwardly to a point below the termination of the first mentioned groove, said last named groove opening into a way or channel formed in the body of the piston; and means for actuating the piston to impart endwise and oscillatory movement thereto to bring the various ports and passages into cooperative relation.

9. In a force feed lubricator, the combination of a pump; an operating shaft; a yoke connected to the piston of the pump; and a wobbling eccentric actuated by the

shaft and connected to a yoke, said eccentric comprising a body member having an eccentrically positioned groove formed in the outer face thereof, said groove being inclined to the axis of said body member; a yoke shaped member having trunnions extending laterally therefrom and connected to the first mentioned yoke, said member be-

ing seated within the groove aforesaid; and a filler block interposed between the ends of 10 said last named yoke member and bearing in the groove.

In testimony whereof I have signed my name to this specification.

THOMAS E. COLEMAN.
